(57) **CLAIM**

The ornamental design for a combined ceiling fan and light fixture, as shown and described.

DESCRIPTION

FIG. 1 is a perspective view of a combined ceiling fan and light fixture showing my new design;

FIG. 2 is a front elevation view thereof, the rear and side views being substantially identical except for the position of the blades;

FIG. 3 is a top plan view thereof; and,

FIG. 4 is a bottom plan view thereof.
